LOAD-HANDLING UTILITY VEHICLE

Eugene G. Humpal and Roy O. Balogh, Cleveland,
Ohio, assignors to The American Coach & Body
Co., Cleveland, Ohio, a corporation of Ohio

Application March 17, 1949; Serial No. 81,956

7 Claims. (Cl. 212—35)

1

This invention relates to a jib crane so mounted on a vehicle that it may be swung into and out of the vehicle and be operated to enable the lifting, transporting and depositing of a load from beyond the confines of the vehicle into the vehicle and vice versa, there being effective means on the vehicle for so swinging the crane and for operating its boom to raise or lower a load suspended therefrom.

Objects of the invention are to provide such device in a very simple form which may be readily mounted on the vehicle and readily swung outwardly therefrom and operated in any position it may be given by manually controlled mechanism on the vehicle. The lifting mechanism comprises a hydraulic cylinder and piston, one attached to the vehicle frame and the other to the boom of the crane, there being on the vehicle a suitable hydraulic pump and a valve and conduits to effect the operation.

Our portable crane mounted and operated as above outlined is illustrated in the drawings hereof and is hereinafter more fully described.

In the drawings, Fig. 1 is a rear elevation of a vehicle equipped with our crane and operating mechanism and showing the crane in idle position suitable for the travel of the vehicle; Fig. 2 is a vertical longitudinal section through the rear portion of the vehicle in a plane indicated by the line 2—2 on Fig. 1 showing the crane extended to the rear of the vehicle; Fig. 3 is a horizontal section in a plane indicated by the line 3—3 on Fig. 1, showing the mechanism for manually swinging the crane; Fig. 4 is a fragmentary plan of the crane and the rear portion of the vehicle, the position of the view being indicated by the line 4—4 on Fig. 1, and showing in full lines the crane in idle position and in broken lines different operative positions; Fig. 5 is a diagram illustrating the arrangement of tank, pump, valves and conduits for hydraulically operating the boom of the crane. Figs. 6, 7 and 8 are diagrams showing the valves in neutral position, and in position for raising the load, and for lowering it, respectively.

In Figs. 1, 2 and 4, 10 indicates the body of a vehicle mounted on a suitable base frame 11 projecting to the rear of the body and supported by wheels indicated at 12 in any suitable manner. The body 10 is provided with a comparatively large opening 15 at its rear end between spaced end walls 16 and 17 and leading from the base frame upwardly substantially to the roof.

The jib crane about to be described is carried by the vehicle on vertical pivots adjacent one

edge of the rear opening 15 of the body and may extend idly across that opening, as shown in Fig. 1, or be swung to the rear for purposes of raising or lowering a load as shown in Fig. 2, or be swung through the opening into the interior of the body to deposit or receive the load as indicated by broken lines in Fig. 4.

Rising from the base frame, along the inner edge of the spaced rear wall 17, is a vertical post 20 in the form of a channel beam. Secured to the top of this post is a short horizontal arm 21 extending inwardly and rearwardly. A downwardly extending bracket 22 is pivoted to this arm on a vertical pivot 23. The crane arm or boom 25 is pivoted at one end to the bracket 22 by a horizontal pivot 26. As indicated in Fig. 4, the boom is bifurcated and passes onto opposite sides of the bracket 22. A hydraulic cylinder 35 is pivoted on a horizontal pivot 38 to the bracket 30. A piston 37 (Fig. 5) within the cylinder has its rod 38 pivotally connected at its upper end at 39 to the boom 25. A suitable cable or rod 40 depends vertically from the outer end of the boom and terminates in a lift hook 41.

The operation of the piston within the cylinder operates to raise or lower the boom, thus raising or lowering the load. A lowered position is indicated in broken lines at 25a in Figs. 1 and 2 and an elevated position at 25b in these figures.

Simple manual means is provided for turning the bracket 30 on its axis and thereby swinging the crane as desired. We effect this by securing a worm wheel 45 to the lower end of the shaft 41 and providing a meshing worm 46, Fig. 3, on a shaft 47 journaled in bearing brackets 48 carried by the base frame. A hand crank 50 is provided to rotate the shaft 47.

The hand crank 50 is pivoted on a radial pivot 51 to the shaft 47 so that the crank when idle may be turned to the rear of the vehicle, as indicated by the broken lines 50a in Fig. 3, so as not to project beyond the side of the vehicle. In use the hand crank is swung outwardly into position indicated in Fig. 1 and thereby provides ready means for turning the worm 46 and thereby rotating the worm wheel and swinging the crane as desired. We have found that it is sufficient to manipulate in this manner simply the lower bracket 30 in swinging the crane, as the cylinder and piston rod and hence the boom and upper bracket turn with the lower bracket.

It will be seen that by reason of the worm and worm wheel operation for swinging the crane the same is irreversible and the crane remains in whatever lateral position is given it by the crank.

Our crane may stand idly across the rear of the vehicle within the confines of the body, as indicated in full lines in Fig. 1, so as to be out of the way of the load carried and still not project beyond the vehicle frame during the travel of the vehicle. Whenever it is desired to use the crane, however, it is readily swung by the crank 50 into a position within the vehicle body, as indicated for instance at 25c in Fig. 4, to engage and raise a load therein and thereafter swing outwardly into a position, indicated for instance at 25d, to deposit the load at the rear of the vehicle. Of course, the reverse operation will function to raise a load from the exterior and swing it into the interior of the vehicle.

As heretofore mentioned, suitable hydraulic means are provided for operating the piston in the cylinder 35 to effect raising or lowering of the boom or holding it stationary. An illustrative arrangement of conduits, valves, etc., for this purpose is indicated in the diagram, Fig. 5.

In Fig. 5, 60 designates a suitable tank carried by the vehicle, 62 a power-operated pump mounted on the vehicle, 64 a manually operable control valve, and 66 a pressure-releasable check valve. Suitable conduits connect the various parts as will be apparent from the following description of the operation.

Oil or other fluid for the operation of the piston in the cylinder is contained in the tank 60, which is provided with a suitable vent or breather 70 to prevent internal pressure. A conduit 61 connects the tank with the pump; a conduit 63 leads from the pump to the control valve 64, and conduits 65 and 67 connect the control valve with the pressure-operated check valve, from which a conduit 68 leads to the cylinder. A conduit 69 leads from the control valve back to the tank.

And a more detailed showing of the manually operated control valve and pilot operated check valve is shown in their different positions in Figs. 6, 7 and 8. The control valve is shown as a casting enclosing an axially movable multi-piston valve member 72. The pilot operated check valve includes an internal valve seat 75, toward which a slidale valve 76 is pressed by a spring 77. The casing 66 also includes a piston 78 having a rod 79 which may pass through the valve seat and abut the end of the valve 76. The spring 77 tends to keep the valve 76 normally seated, thus closing the passageway from the conduit 67 from the control valve. However, when the pressure is admitted by the control valve to the conduit 65 it acts against the piston 78 to unseat the valve.

Fig. 6 shows the valves in a neutral position, which is a holding position for the load. When the valve member 72 is in the position shown in Fig. 6, the pump conduits 63 are out of communication with either the conduit 65 or 67 leading from the control valve. However, the pump conduits are in communication with conduit 69 leading to the tank. This allows the pump to operate continuously though idly. As the check valve 76 is held seated by its spring 77, the fluid in the conduit 68 and in the lower portion of the cylinder holds the load in whatever position it may have.

To raise the load the control valve 72 is shifted into the position shown in Fig. 7. In this position one of the pump conduits 63 is connected with the conduit 67 leading to the valve seat of the check valve. The pressure through the conduit 67 unseats the valve, against the action of its spring 77, so that the fluid is admitted to the conduit

68 and passes to the cylinder, thus raising the load.

To lower the load the valve member 72 is shifted to the opposite end of its casing. In this position, shown in Fig. 8, the conduit 65 is connected with the pump while the conduit 67 becomes connected with the tank through the diagonal passage in the end of the valve member 72. The result is that fluid under pressure is admitted to the conduit 65 to act against the piston 78 of the check valve to overcome the action of the spring 77 and unseat the valve. This connects the conduit 68 from the cylinder with the return conduit 67, so that the fluid may pass from the cylinder back to the tank. The weight of the load forces the fluid in the cylinder in this direction as the load lowers by gravity. When the lowering has reached the proper amount, the shifting of the valve member 72 back to neutral position stops the lowering operation and holds any load then suspended on the hook.

Figs. 6 and 7 and 8 indicate at 80 a pressure relief valve of the usual type which is normally idle but may connect the conduit 67 with the conduit 69 back to the tank if the pressure is excessive. This prevents the crane being operated to pick up a heavier load than that for which it is intended.

It will be understood from the description given that we have provided not only a simple jib crane mounted in a convenient manner adjacent the opening to the vehicle body and manually swingable laterally into any position desired, but we have also provided a very convenient hydraulic arrangement effective for raising, lowering and holding the load by fluid pressure delivered by a pump operated by suitable power means on the vehicle. The manual control valve for such hydraulic operation is preferably located adjacent the crank 50 for swinging the crane laterally so that all operations may be readily effected by an operator standing on the ground at the side of the vehicle and adjacent the rear end, where he may readily observe the operation.

We claim:

1. The combination of a vehicle having a body with an opening to the interior, a pair of brackets carried by the body one above the other, each bracket being pivotally mounted on a vertical pivot, a boom pivoted to the upper bracket by a horizontal pivot, a piston and cylinder couple, one member of which is pivoted to the lower bracket on a horizontal pivot and the other member of which is pivoted to the intermediate region of the boom, the lower bracket being swiveled by a vertical shaft rotatably mounted in the body, a worm wheel on said shaft, a worm meshing therewith and a crank for operating the worm.

2. The combination of a vehicle having a body with an opening therein, an upright post carried by the body adjacent one vertical edge of the opening, a fixed arm at the top of said post, a bracket pivoted on a vertical pivot to said arm, another bracket pivoted on a vertical pivot to the floor frame of the vehicle, said two vertical pivots axially aligning, a boom pivoted on a horizontal pivot to the upper bracket, and extensible means pivoted at its lower end to the lower bracket on a horizontal pivot and pivoted to the boom on a horizontal pivot, and a load-engaging member depending from the boom.

3. The combination of a vehicle having a body with an opening at its rear end, an upright post extending along one edge of the body opening, a horizontal arm at the top of the post, a bracket

pivoted on a vertical pivot to the arm, a vertical shaft mounted in the base frame of the vehicle in alignment with said vertical pivot, a bracket carried by the shaft, a boom pivoted on a horizontal pivot to the upper bracket, extensible means pivoted on a horizontal pivot to the lower bracket and pivoted at its upper end to the boom, a load supporting member depending from the free end of the boom, means for operating said extensible mechanism to raise the boom, and means for turning said shaft to swing the boom and extensible mechanism laterally.

4. The combination of a vehicle having a base frame and a body with an opening therein, a vertical post carried by the body adjacent one vertical edge of the opening, an arm rigidly carried by the top of the post, a bracket pivoted to the arm on a vertical pivot, a shaft rotatably mounted in the base frame in axial alignment with said vertical pivot, a bracket carried by said shaft, a boom pivoted to the first-mentioned bracket, a piston and cylinder couple pivoted at one end to the second-mentioned bracket and at the other end to the boom, a manually operated shaft carried by the base frame, and gearing connecting the last-mentioned shaft with said vertical shaft.

5. The combination of a vehicle having a base frame and a body with an opening therein, a vertical post carried by the body adjacent one vertical edge of the opening, an arm rigidly carried by the top of the post, a bracket pivoted to the arm on a vertical pivot, a vertical shaft mounted in the base frame in axial alignment with said vertical pivot, a bracket carried by said shaft, a boom pivoted to the first-mentioned bracket, extensible means pivoted at one end to the second-mentioned bracket and at the other end to the boom, a horizontal shaft carried by the base frame, gearing connecting said horizontal shaft with said vertical shaft, and a crank pivoted to the outer end of the horizontal shaft and adapted to stand within the side confines of the vehicle or be in a position beyond the side of the vehicle.

6. The combination with a vehicle having a body with an opening at the rear end, a jib crane pivoted to the body on vertical pivots adjacent one vertical edge of the opening, a piston and cylinder couple for operating the boom of the jib crane, means geared with the jib crane to swing it laterally, said means terminating in a manual crank at the rear of the vehicle adapted to stand at the side thereof, a power operated pump on the vehicle, a manual control valve and conduits on the vehicle connecting the pump with the cylinder, said manual control valve being located adjacent said crank whereby the load supported by the jib crane may be raised, lowered, swung laterally by an operator at the side of the vehicle.

7. The combination of a vehicle having a body with an entrance opening, a jib crane comprising a boom pivoted at one end to the body and a piston and cylinder couple pivoted at one end to the body and at the other end to the boom, the pivots to the body being adjacent one vertical edge of said opening, means for swinging the boom and piston and cylinder couple laterally, a power-operated pump on the vehicle, a manual control valve and a pilot-operated check valve on the vehicle, and conduits connecting the pump, control valve and check valve with the cylinder to enable the actuation of the piston to raise the load and to hold the piston stationary to hold the load and to allow the lowering of the piston by the weight of the load.
